(57) **CLAIM**

The ornamental design for an electronic module for recording and transmitting, as shown and described.

DESCRIPTION

FIG. 1 is a perspective view of an electronic module for recording and transmitting showing our new design; FIG. 2 is a front elevational view of the electronic module for recording and transmitting of FIG. 1; FIG. 3 is a rear elevational view of the electronic module for recording and transmitting of FIG. 1; FIG. 4 is a top plan view of the electronic module for recording and transmitting of FIG. 1; FIG. 5 is a bottom plan view of the electronic module for recording and transmitting of FIG. 1; FIG. 6 is a right side elevational view of the electronic module for recording and transmitting of FIG. 1; and, FIG. 7 is a left side elevational view of the electronic module for recording and transmitting of FIG. 1. The broken lines shown in the drawings illustrate portions of the electronic module for recording and transmitting that form no part of the claimed design.
